CRANKPIN GRINDING MACHINE

Herbert A. Silven, Worcester, Mass., assignor to
 Norton Company, Worcester, Mass., a corpora-
 tion of Massachusetts

Application September 29, 1934, Serial No. 746,158

15 Claims. (Cl. 51—72)

This invention relates to grinding machines, and more particularly to a control mechanism for a hydraulically driven cylindrical grinding machine.

Heretofore, various types of hydraulic drive mechanisms have been applied to control the various moving parts of a grinding machine, namely, longitudinal table traverse, transverse movement of the wheel toward and from the work, and movement of the steadyrest shoe toward and from its operative position in engagement with the work. In most of the previous constructions, the control of the hydraulically actuated part has been under individual and separate control requiring the operator to move several control levers in operation of the machine.

In certain types of cylindrical grinding, such as the grinding of a cylindrical crankpin of a crankshaft, it is necessary for the wheel and the steadyrest shoe to be removed from engagement with the work through a considerable distance to separate the wheel and work rest sufficiently from the work to allow the longitudinal traversing movement of the work table to position the next pin opposite the grinding wheel. Heretofore, to accomplish this result, it has been necessary to either manually or hydraulically move the wheel to its rearward position and then by means of separate control to remove the work rest shoe to its inoperative position. Similarly, when it is desired to grind a given pin on a crankshaft, it has been necessary for the operator to advance the steadyrest shoe into operative engagement with the surface of the work either manually or by the operation of a manually controlled mechanism before the wheel slide control is moved to bring the wheel into grinding relation with the work piece, but this has necessitated a considerable amount of the operator's attention in seeing to it that the work rest is in engagement with the work before the grinding operation is started and not only removing the grinding wheel but also removing the work rest after the grinding operation has been completed.

It is the primary object of this invention to provide a wheel feeding mechanism and a work rest positioning mechanism which are operated automatically to simultaneously move the work rest and the grinding wheel either toward or from the work to bring the same into operative engagement with or remove the same from operative engagement with the work piece being ground.

It is a further object of this invention to provide an interlocked hydraulic control mechanism for hydraulically moving the work rest and the wheel slide either simultaneously toward or simultaneously away from the work piece being ground. 5

It is another object of this invention to provide a hydraulically driven grinding machine with a single control lever which serves to admit fluid under pressure to simultaneously separate the wheel and work rest from engagement with the work or to simultaneously move the wheel and rest into operative engagement with the work. 10

It is still another object of this invention to provide a main control valve which serves as a hydraulic interlock to prevent longitudinal movement of the work support when the work rest shoe is in operative engagement with the work. 15

In the prior practice in the grinding of crankshafts, it has been necessary to provide adequate splash guards to prevent the coolant fluid from being thrown to the front of the machine onto the floor or onto the various parts of the mechanisms on the front of the machine, as well as to prevent the operator from being soaked thereby. Splash guards have been provided which are easily and readily removed from the table, so that the operator may after finish grinding a crankshaft manually remove the guards and then lift the crankshaft from the machine and place a new crankshaft to be ground therein, and then manually place the guards in an operative position. In some machines, the guards have been affixed to the table, and it has been necessary for the operator to lift a heavy crank- 20 25 30 35 40 45 50

shaft up over the guards to place it in position in the work holders, and similarly upon completion of the grinding operation, it has been necessary for the operator to reach up over the guard and lift the shaft out of the machine. Each of these prior practices has required undue exertion on the part of the operator and has tended to impair the efficiency of the machine. 50

It is another object of this invention to provide a movable splash guard, which is arranged so that it is moved automatically into an operating position at the start of the grinding operation and is moved to an inoperative position after the grinding operation has been completed. 45

It is still another object of this invention to provide a guard having an upper pivotally mounted portion which may be moved to an inoperative position automatically as the work rest is withdrawn to an inoperative position. 55

It is a further object of this invention to provide a movable splash guard which is preferably affixed to the work rest and arranged so that it may be automatically moved to an operative or inoperative position in timed relation with the movement of the work rest shoe into or out of engagement with the work.

It is another object of this invention to provide a grinding wheel, work shoe, and a splash guard which are arranged to be automatically and simultaneously moved either into or away from an operative position.

Other objects will be apparent from the following disclosure.

15 One embodiment of this invention has been illustrated in the drawings, in which like reference numerals indicate like parts:

Fig. 1 is a front elevation of a hydraulically driven crank-pin grinding machine embodying 20 this invention.

Fig. 2 is a fragmentary diagrammatic perspective view showing the hydraulic system and the control levers and valves;

Fig. 3 is a right-hand end view of the machine, 25 having parts broken away and shown in section to more clearly bring out the constructional details of the machine;

Fig. 4 is a fragmentary elevation, on an enlarged scale, showing the work rest and its operating 30 parts in section;

Fig. 5 is a longitudinal sectional view showing the details of the work clamping and releasing mechanism; and

Fig. 6 is a cross-sectional view, taken approxi- 35 mately on the line 6—6 of Fig. 4, showing the splash guard.

This invention consists broadly in providing a hydraulically driven machine, such as a double head hydraulically driven crankpin grinding machine, with hydraulic control for the wheel slide actuating mechanism and the work rest actuating mechanism which is arranged so as to permit the steadyrest shoe and grinding wheel to be moved simultaneously into or out of operative 45 engagement with the work before or after grinding. A machine embodying this invention has been illustrated in the drawings comprising a double head rotatable work support which is mounted on a longitudinally movable carriage. 50 The carriage work table is moved longitudinally by a fluid pressure mechanism. A grinding wheel slide is provided for a transverse movement to move the grinding wheel transversely relatively toward or from the work piece by means of a 55 fluid pressure piston and cylinder mechanism. A work rest is provided for movement into or out of engagement with the surface of the work piece being ground and is preferably controlled by a fluid pressure piston and cylinder mecha- 60 nism. A control valve is provided which is interconnected between the wheel slide actuating cylinder and the work rest actuating cylinder so that when the valve is moved to one position, fluid is admitted to cause the grinding wheel and 65 the work rest to separate and move to an inoperative position away from engagement with the work; and when moved to a second position, serves to admit fluid to the feed cylinder and work rest cylinder to simultaneously move the 70 work rest shoe and the grinding wheel into operative engagement with the work piece being ground.

The fluid pressure system is provided with a main control valve which is arranged to prevent longitudinal movement of the work support when 75 either the grinding wheel or work rest or both

of them are in operative engagement with the work.

A movable splash guard is provided which is preferably to be moved automatically to and from an operating position. The wheel feeding 5 mechanism, the work rest shoe actuating mechanism and the splash guard actuating mechanism are preferably interconnected so that the grinding wheel, the shoe and the guard may be moved automatically and simultaneously into or out of 10 operative position before and after the grinding operation.

A machine illustrating one embodiment of this invention has been shown in the drawings, having the base 10 which is arranged to support a 15 transversely movable wheel slide 11 mounted on the usual V-way 12 and flat way 13, such as is a well known and common practice in the grinding machine art. The base 10 also supports a work supporting table 15 which is arranged for a longitudinal movement relative to the base 10 on a V-way 16 and flat way 17. The wheel slide 11 rotatably supports a grinding wheel 20 which is mounted on one end of a wheel spindle 21. The grinding wheel may be rotated by any suitable 25 driving mechanism, such as are well known in the grinding art. For simplicity of illustration, a motor driven wheel spindle drive has been illustrated comprising an electric motor 23 mounted on the wheel slide 11. The motor 23 is provided 30 with a driving pulley 24 which is connected by driving belts 25 with a driven pulley 26 on the outer end of the wheel spindle 21. The driving belt 25 may be an ordinary flat belt or may comprise a multiple V-type belt drive in which 35 a plurality of V shaped belts ride in a plurality of grooves on the driven pulley.

A suitable work supporting and rotating mechanism is provided comprising a pair of opposed double work supporting and rotating heads which 40 engage and grip opposite ends of a crankshaft to be ground. Such a mechanism may be similar, for example, to the construction illustrated in the prior patent to Silven and Belden No. 1,837,342 dated December 22, 1931, to which reference may 45 be had for details of disclosure as to the work head and the work clamping mechanism. In the preferred construction, a pair of opposed work supporting and rotating heads 30 and 31 are mounted on the work supporting table 15 and may 50 be formed integrally therewith or adjustably mounted thereon. In order that the crankshaft may be rotated uniformly from opposite ends, it is desirable to provide a synchronized work drive for rotating the two opposed work clamping 55 heads. As illustrated in the drawings, a crank- shaft 32 may have its opposite ends clamped in opposed rotatable work holders 33 (only one of which has been illustrated) which are rigidly affixed to face plates 34 mounted on the inner end 60 of each work rotating spindle 35. In order that the work spindles may be synchronously rotated, a driving mechanism is provided including a drive shaft 37 in the base of the machine, which is rotated from any suitable source of power such as is well known in the art. The positively driven shaft 37 may be connected by means of a clutch 38 to drive a shaft 39, also rotatably mounted in the base. The shaft 39 carries a sprocket 40 which drives through a link chain 41 to a sprocket 42 mounted on a longitudinally extending shaft 43. The shaft 43 is supported in bearings 44 depending from the work table 15. The shaft 43 carries at its outer ends sprockets 45 which drive link chains 46. The link chains 46 engage 70

sprockets 47 mounted on the end of each spindle 35 to rotate the same.

In the preferred construction, the heads 30 and 31 are adjustably mounted on the work table 15 so that they may be adjusted longitudinally relative thereto to accommodate crankshafts of different lengths. To permit longitudinal movement of the head, it is desirable to provide a driving mechanism for the work spindles which is fixed relative to the table. In the drawings, the casings 48 are provided rigidly supported on the table 15 and are arranged independent of the heads 30 or 31, so that the heads may be adjusted longitudinally of the table without disturbing the driving mechanism. Details of this construction are illustrated in Fig. 5, which shows the gear casing 48 as independent of the head 31.

The driven sprockets 47 are keyed to sleeves 50, only one of which has been illustrated in the drawings. The sleeve 50 is slidably keyed within the work supporting spindles 35 so as to enable the work heads 30 and 31 to be adjusted longitudinally on the table 15 without disturbing the driving mechanism at each end of the table which is contained within the casings 48 rigidly fixed to opposite ends of the table 15.

The work clamping mechanism is provided to clamp the work in the opposed work heads. Details of the clamping device have not been illustrated in the present case, since they do not constitute part of the present invention. For details of construction of the work heads, reference may be had to the prior patent to Silven and Belden No. 1,837,342. The work clamping mechanism in the preferred construction comprises a spring actuated toggle which controls the movement of the clamping jaw to clamp the work rigidly in position on the machine. As illustrated in Fig. 5, a piston 55 and cylinder 56 for unclamping the work may be mounted in axial alignment with the work rotating spindle, if desired, instead of being connected to an offset piston and cylinder, as illustrated in the prior Silven and Belden patent. The work table may be traversed manually by means of a hand wheel 60 mounted on the outer end of a shaft 61 which also carries the gear 62 meshing with a gear 63. The gear 63 in turn meshes with a rack bar 64 mounted on the front of the work table 15.

The wheel slide 11 may be fed toward and from the work manually, for example, by means of a hand wheel 68 mounted on a shaft 69. The shaft 69 carries a gear 70 meshing with a gear 71 mounted on the outer end of a shaft 72. The inner end of the shaft 72 is formed as a feed screw 73 meshing with a nut 74 depending from the wheel slide 11. It will be readily appreciated from this construction that manual rotation of the feed wheel 68 in either direction serves to cause a movement of the grinding wheel either toward or from the work, as desired.

In the preferred construction, the grinding wheel slide and the work supporting table may be moved hydraulically by means of a fluid pressure system including an interlocked arrangement between the transversely movable wheel slide and the longitudinally movable work table so that only one of these mechanisms may be moved hydraulically at a given time. For details of disclosure of this mechanism, reference may be had to the prior patent to Belden and Silven No. 1,905,127 dated April 25, 1933. Such a fluid pressure mechanism may comprise a tank or sump 90 in the base, a fluid pressure pump 91 which is arranged to convey fluid to a main con-

trol valve 92. The main control valve is actuated by a manually operable lever 93 and is arranged to direct fluid under pressure through a pipe 94 to a wheel feed control valve 95 or through pipe 96 to a work table traverse control valve 97. The valve 97 is connected by pipes 98 and 99 with opposite ends of a cylinder 100 to admit fluid on opposite sides of a piston 101 which is connected by a piston rod 102 with the table 15. A manually operable lever 103 serves to actuate valve 107 so as to admit fluid to either end of the cylinder 100 so as to cause the table 15 to move in the desired direction to position the work piece relative to the grinding wheel 20.

Fluid passing through the valve 95 is admitted either through pipe 105 or 106 to cylinder 107 to cylinder chambers on opposite sides of a piston 108 which is connected by a piston rod 109 to the rear end of feed screw 13 so as to cause either a forward or reverse feeding movement of the grinding wheel. The valve 95 is preferably controlled by a manually operable lever 110 which is operatively connected to move the valve 95 so as to admit fluid to cylinder 107 and cause a forward or rearward feeding movement of the grinding wheel 26. The fluid pressure system for controlling the transverse movement of the wheel slide 11 and the longitudinal movement of the work table 15 are interconnected or interlocked by means of the main control valve 92 so that fluid under pressure may be admitted to move either the grinding wheel or the work while excluding it from the other. For details of disclosure as to the operation of the interlock, reference may be had to the prior Patent No. 1,905,127.

In a grinding machine of the type used for grinding crankshafts, it is essential that a suitable steadyrest be provided for steadyng the crankshaft 32 during the grinding operation. In the preferred construction, a fluid pressure actuated work rest is provided comprising a work steadyrest shoe 115 mounted on a transversely movable slide 116 which is supported in a steadyrest frame 117. The steadyrest support is preferably rigidly fixed to the base in a position so that the shoe 115 engages the work at a point directly opposite the grinding wheel 20, so that the work table may be indexed longitudinally of the base 10 to position the work relative to the grinding wheel without disturbing the position of the work rest which is always in a fixed position opposite to the grinding wheel. The steadyrest shoe 115 is preferably moved to and from an operating position by a fluid pressure mechanism comprising a cylinder 118 and piston 119. The piston 119 is connected by a piston rod 120 with a bracket 121 depending from a slide 122 which is supported within the steadyrest frame 117. The slide 122 in turn supports the slide 116 and shoe 115, so that when fluid under pressure is admitted to either end of cylinder 118, a transverse movement is transmitted to the work engaging shoe 115 to move the same either toward or from the work.

In order that the shoe may be maintained in the desired adjusted position, a manually operable mechanism is provided to adjust the position of the slide 116 relative to the slide 122. Such a mechanism as illustrated in the drawings may comprise a screw 123 which is fixed at one end to the slide 116 and passes through a threaded nut 124 in the slide 122. A knob 125 on the outer end of the screw 123 serves to rotate the screw and cause a relative movement between the slide 122 and the slide 116.

116 and 122. It will be readily appreciated from the foregoing disclosure that the steadyrest may be set up for a grinding operation so that fluid under pressure will move the shoe 115 into engagement with the work and maintain it in engagement with the work by fluid under pressure, if desired; it being necessary to merely adjust the position of the knob 125 to relatively position slides 116 and 122. Or, in the preferred manner of operation, the fluid pressure mechanism may be used merely as a positioning mechanism to rapidly move the shoe 115 into and out of operative engagement with the work. In such a case, the fluid pressure piston 119 on its forward movement moves until the projecting end of the piston rod 120 engages the end of the cylinder 118, and the work shoe 115 is maintained in operative engagement with the crankpin being ground by manually manipulating the knob 125.

20 To attain one of the objects of this invention, namely, to cause the grinding wheel and the work rest to rapidly approach or separate from engagement with the work before and after grinding, a suitable arrangement of the fluid pressure mechanism is provided which enables the grinding wheel and the work rest shoe to be moved simultaneously either toward or from engagement with the work. In order that the steadyrest shoe 115 may be moved toward and from engagement with the work simultaneously with and in timed relation with the grinding wheel 20, suitable fluid pressure connections are provided including pipes 130 and 131 which are connected with pipes 105 and 106 leading from the wheel feed control valve 95. The pipes 105, 106, 130 and 131 are so connected between the wheel feed control valve 95 and cylinders 107 and 118. Admission of fluid to cause a forward feeding movement of the grinding wheel 20 also serves to admit fluid to cylinder 118 so as to cause a forward approaching movement of the work shoe 115 so that the grinding wheel 20 and the work steadyng shoe 115 may be moved simultaneously into operative engagement with the work. Similarly, when the control lever 45 110 is moved to change the position of valve 95 so as to cause a rearward movement of the grinding wheel 20 to separate the wheel from the work, fluid is also admitted through pipe 131 to cylinder 118 to cause the work steadyng shoe 115 to be simultaneously moved away from operative engagement with the work. It will be readily appreciated from the foregoing disclosure that by manipulation of the wheel feed control lever 110, the grinding wheel 20 and the work steadyng shoe 115 may be moved either simultaneously toward the work or simultaneously away from the work, thereby eliminating the necessity of an individual control for each element when it is necessary to change the position of the table from one pin to the next, to separate the wheel and the steadyrest shoe by a distance sufficient to allow the clearance of the various crank arms as the table is traversed.

60 To prevent coolant fluid from splashing to the front of the machine and wetting the floor and the operator, a suitable splash guard is provided. In the preferred construction, the steadyrest frame 111 is mounted fixedly on the base 10 and a splash guard 140 is rigidly fastened to the front 70 end of the steadyrest member. The guard 140 is arranged to catch the splash of coolant fluid and direct it to the down slope of the table, so that it is conveyed back to the coolant fluid sump at the rear of the machine.

75 To attain one of the objects of this invention,

a splash guard is provided which is movable automatically to and from an operating position to eliminate the necessity of the operator lifting a heavy crankshaft up over the splash guard or requiring the operator to remove splash guard during each operation. A movable guard may comprise a movable guard member 141 which is hinged to the fixed guard 140 by hinges 142 and 143. Suitable springs 144 and 145 serve to maintain the upper portion of the guard 141 normally in an operating or vertical position.

In order that the guard 141 may be moved into an inoperative position to permit the operator to load and unload the machine without the necessity of lifting a heavy crankshaft or work piece 15 up and over the top of a relatively high splash guard, an automatically actuated mechanism is provided to move the guard 141 to and from an operative position. In order that the splash guard 141 may be moved to an inoperative position, a T-shaped member 146 is mounted on the steadyrest slide 116. When the steadyrest shoe 115 and slide 116 are moved rearwardly, that is, toward the right, as viewed in Fig. 4, a narrow, vertical portion 147 of the T-shaped member 146 25 rides in a slot 148 in the guard 141, and the horizontal portions 149 of the T engage the guard 141 and continued movement of the slide 116 rocks the guard 141 into the position 141a, as indicated in Fig. 4. Similarly, when lever 110 is moved into a position to cause the work shoe 115 and grinding wheel 20 to be moved into operative engagement with the work, the withdrawal of the T-shaped member 146 serves to allow the released tension of the springs 144 and 145 to automatically and simultaneously return the splash guard 141 to an operative vertical position, as indicated in Fig. 4.

For certain types of grinding, it may be desirable to provide an independent control for the work rest, to permit the work steadyng shoe to be moved into operative engagement with the work independent of the grinding wheel 20. A work rest control valve 150 is provided within the frame 111. This valve is preferably located 40 in the pipe line 130 so that fluid under pressure may be admitted through pipe 130 to cylinder 118 simultaneously with admission of fluid to move the grinding wheel 20. A plunger type valve 150 is provided having a control knob 151 45 on the outer surface of the steadyrest. When it is desired to operate the steadyrest shoe 115 independent of the wheel slide 11, the operator pulls the knob 151 to move the valve 150 toward the left, as viewed in Fig. 3. This movement 50 serves to prevent passage of fluid through the pipe 130 to the cylinder 118. In this position of the valve, the operator may by manipulation of the lever 110 cause the grinding wheel to move either toward or from the work without causing 55 a movement of the work rest.

In case it is desired to merely utilize the fluid pressure movement of the steadyrest shoe 115 as a rapid positioning movement and to maintain the shoe in operative contact with the work during grinding by manually rotating the adjusting knob 125, it is desirable that the splash guard 141 be moved into an operating position when the grinding wheel is brought into operative engagement with the work. In case it is desired to 65 grind off rough spots on the work before the work rest is brought into operative engagement with the work piece, it is desirable that the work rest be moved into a position adjacent but out of contact with the rough piece of work and that 70 75

the splash guard be moved into an operative position to prevent the splash of coolant fluid toward the front of the machine. The steady-rest mechanism and splash guard are arranged so that the shoe 115 may be adjusted relative to the fluid pressure piston 119 so that the shoe does not contact with the work when the piston is brought up against the end of the cylinder 118. In such a case, the splash guard and grinding wheel are moved simultaneously into an operative position for rough grinding the work. After the rough grinding operation has been completed and the rough spots ground off the periphery of the work piece, the manually adjustable knob 125 may then be rotated to move the work steadyng shoe 115 into operative contact with the work piece.

In certain types of grinding, such as grinding rough crankpins, it is desirable to bring the grinding wheel into engagement with the work to grind off the rough spots on the work before the work rest is brought into operative engagement therewith. The operator first moves the control lever 110 to cause the grinding wheel 20 to approach into operative engagement with the work. The operator, after the desired grinding has been accomplished, then pushes the control knob 151 toward the right, as viewed in Fig. 3, to open to the valve 150 and admit fluid under pressure through pipe 130 into the cylinder 118 to cause the shoe 115 to be brought into operative engagement with the surface of the work piece. In such an arrangement of the valves, the return movement of the steadyrest shoe is connected so that the steadyrest shoe 115 and the grinding wheel 20 move simultaneously away from engagement with the work. Only the forward movement of the steadyrest shoe is controlled independent of the wheel slide.

An interlock may be provided between the work rest and the table traverse, if desired, so that the table cannot be traversed when the work shoe is in engagement with the work. Such a mechanism may comprise an interlock which locks the table traverse control lever when the grinding wheel and work shoe are in engagement with the work. A bell crank lever 160 is pivotally mounted on a stud 161 which is fixed to the steadyrest frame 117. The short arm 162 of the bell crank lever 160 is provided with a notch 163 which is arranged to engage a pin 164 (Fig. 4) on the table traverse control lever 103 so as to prevent movement of lever 103 when the grinding wheel 20 and work rest shoe 115 are in an operative position relative to the work. A spring (not shown) tends to normally hold the bell crank lever 160 so that notch 163 engages pin 164 to prevent a traversing movement of the work supporting table.

A pin 165 is mounted on steadyrest slide 116 and passes through an elongated slot 166 in the slide 122 and the steadyrest frame 117. When the grinding wheel 20 and steadyrest shoe 115 are moved to inoperative positions away from the work, the pin 165 moves into engagement with the long arm of the bell crank lever 160 and moves it into the position 160a (Fig. 4) against the tension of the spring (not shown). This movement of the bell crank lever 160 rocks the short arm 162 into position 162a, thereby disengaging notch 163 and unlocking pin 164 so as to allow movement of the table traverse control lever 103. Similarly, when the grinding wheel 20 and work shoe 115 move into engagement with the work, the released tension of the spring serves

to rock the lever 160 in a counterclockwise direction (Fig. 4) to lock the lever 103 and prevent a traversing movement of the work table.

The operation of this mechanism will be readily apparent from the foregoing disclosure. The operator first mounts a crankshaft to be ground in the work head, then by manipulation of the main control lever releases fluid under pressure to the cylinder 55, allowing the released tension of the springs in the clamping mechanism to clamp the work rigidly in place. Movement of the control lever into a second position then serves to engage the clutch 38 to cause the work to rotate, and movement of control lever 103 serves to cause a longitudinal movement of the table 15 to bring the desired crankpin into operative engagement with the grinding wheel 20. In this position of the parts, the operator by manipulation of the control lever 110 may then cause a simultaneous movement of the grinding wheel 20 and the work steadyng shoe 115 into operative engagement with the work, or a simultaneous withdrawal of the grinding wheel 20 and work rest 115, as desired. At the same time, the splash guard is automatically moved toward and from an operating position, so that when the steadyrest and the grinding wheel are moved to a point remote from their operative position, the splash guard 114 is rocked to an inoperative position, allowing the operator ready access to unload and load crankshafts in the machine without the necessity of lifting a heavy crankshaft up and over a high splash guard or avoiding the necessity of the operator having to lift the splash guard off the machine at each loading operation.

Having thus described the invention, what is claimed as new and desired to secure by Letters Patent is:

1. A grinding machine comprising a work support to rotatably support a cylindrical work piece, a rotatable grinding wheel, a transversely movable wheel slide supporting said wheel which is movable towards and from said work support to grind the work, a work steadyng rest having a work engaging shoe which is movable into or out of engagement with the work to steady the same during grinding, and a fluid pressure operated mechanism including a control valve to simultaneously move the wheel and shoe either towards or away from the work. 40

2. A grinding machine comprising a work support to rotatably support a cylindrical work piece, a rotatable grinding wheel, a transversely movable wheel slide supporting said wheel, a fluid pressure operated mechanism to move said slide towards or from said work support, a work steadyng rest having a work engaging shoe, a fluid pressure operated mechanism to move said shoe into or out of engagement with the work to steady the same during grinding, and a fluid pressure system including a control valve to simultaneously move the wheel and shoe either towards or from the work. 55

3. In a cylindrical grinding machine, a longitudinally movable rotatable work support, a rotatable grinding wheel, a transversely movable wheel slide supporting said wheel, a fluid pressure piston and cylinder operatively connected to move said slide, a work rest having a work steadyng shoe, a fluid pressure piston and cylinder operatively connected to move said shoe into or out of engagement with said work, and a fluid pressure system including a control valve arranged to admit fluid under pressure simultaneously to each of said 70 75

cylinders to cause the grinding wheel and shoe to move simultaneously towards the work to support and grind the same.

4. In a cylindrical grinding machine, a longitudinally movable rotatable work support, a rotatable grinding wheel, a transversely movable wheel slide supporting said wheel, a fluid pressure piston and cylinder operatively connected to move said slide, a work rest having a work steadyng shoe, a fluid pressure piston and cylinder operatively connected to move said shoe into or out of engagement with said work, and a fluid pressure system including a control valve arranged to admit fluid under pressure simultaneously to each of said cylinders to cause the grinding wheel and shoe to move simultaneously away from engagement with the work after the grinding operation has been completed.

5. A grinding machine comprising a base, a longitudinally movable work support mounted thereon, rotatable work supporting members on said table, a wheel slide which rotatably supports a grinding wheel for transverse movement relative to said base, a work supporting shoe arranged to support and steady the work during grinding, a fluid pressure system including a piston and cylinder operatively connected to move said wheel slide transversely relative to the base either toward or from the work, a second fluid pressure piston and cylinder operatively connected to cause the shoe to approach or recede from engagement with the work, and means including a manually operable control valve to cause the grinding wheel and the work rest to simultaneously approach the work piece to support and grind the same and to simultaneously recede therefrom after a predetermined grinding operation has been completed.

6. In a cylindrical grinding machine, a longitudinally movable rotatable work support, a fluid pressure piston and cylinder operatively connected to move said support longitudinally of said machine, a rotatable grinding wheel, a transversely movable wheel slide supporting said wheel, a fluid pressure piston and cylinder operatively connected to move said slide toward or from the work, a work rest having a work steadyng shoe arranged to steady and support the work piece, a fluid pressure piston and cylinder operatively connected to move said shoe into or out of engagement with the work, a fluid pressure system including a control valve arranged to admit fluid under pressure simultaneously to the second and third cylinders to cause a simultaneous movement of the grinding wheel and shoe either toward or from the work piece, and a main control valve arranged to prevent movement of the grinding wheel or shoe when the work table is being traversed.

7. A grinding machine having a base, a work support and a wheel slide which are slidably mounted thereon and arranged for a relative longitudinal and transverse movement relative thereto, a rotatable work support on the longitudinally movable member which is arranged to support a cylindrical work piece in operative relation with the grinding wheel, fluid pressure actuated system including a piston and cylinder arranged to move said member longitudinally relative to the base to position the work piece relative to the grinding wheel, a second fluid pressure piston and cylinder operatively connected to move the wheel slide transversely toward and from the work axis, a fluid pressure piston and cylinder actuated work rest arranged to engage and steady the work during grinding, and means

including a fluid pressure control valve interconnected between the wheel slide cylinder and the work rest cylinder which is so arranged that the grinding wheel and the work rest are simultaneously moved into operative relation with the surface of the work before the grinding operation and simultaneously withdrawn therefrom after the grinding operation has been completed.

8. A grinding machine comprising a base, a longitudinally movable work supporting table thereon, a rotatable work support on said table, a grinding wheel slide carrying a rotatable grinding wheel mounted for transverse movement relative to the base to cause a transverse feeding movement of the grinding wheel, a fluid pressure system including a piston and cylinder arranged to traverse the work support longitudinally relative to the base, a second fluid pressure piston and cylinder operatively connected to cause a transverse movement of the grinding wheel slide toward and from the work support, a work rest arranged to engage and support the periphery of the work, a fluid pressure piston and cylinder operatively connected to move said rest either toward or from the work, a fluid pressure system including interconnections between the wheel slide actuating cylinder and the work rest actuating cylinder, and a manually operable valve in said system arranged to simultaneously admit fluid under pressure to the wheel slide and the work rest cylinder to simultaneously cause the grinding wheel and the work rest to approach the work and/or to simultaneously recede from engagement with the work after it has been ground to a predetermined size.

9. A grinding machine comprising a rotatable grinding wheel, a longitudinally movable rotatable work support, means including a control lever to traverse said support, a work rest having a work engaging shoe, means to move said shoe into or out of engagement with the work, and means actuated by movement of said shoe towards an operative position to lock said lever and prevent a traversing movement of the work support when the shoe is in an operative position.

10. A grinding machine comprising a rotatable grinding wheel, a longitudinally movable rotatable work support, means including a control lever to traverse said support, a work rest having a work engaging shoe, means to move said shoe into or out of engagement with the work, and an interlock between said steadyrest shoe and traverse control lever which positively locks the control lever in a neutral position to prevent traverse of the work support when the shoe is in an operative position.

11. In a cylindrical grinding machine, a rotatable grinding wheel, a rotatable work support, a work rest having a work engaging shoe which is movable into and out of engagement with the work, means to move said shoe toward and from the work, a movable splash guard on the opposite side of the work support from the grinding wheel which is movable relative to said work support either to or from an operative position, and means to cause said work engaging shoe to move into operative engagement with the work and the guard to move simultaneously into an operative position before grinding is started and to simultaneously move to inoperative positions after the grinding operation has been completed.

12. A grinding machine comprising a transversely movable rotatable grinding wheel, a rotatable work support, a work rest having a work engaging shoe which is movable into and out of

engagement with the work, means to move said shoe toward and from the work, a movable splash guard on the opposite side of the work support from the grinding wheel which is movable to and from an operative position, and means to cause said grinding wheel and guard to move simultaneously into operative positions before the grinding operation and to move simultaneously to inoperative positions after the grinding operation has been completed.

13. In a cylindrical grinding machine, a rotatable grinding wheel, a rotatable work support, a work steadyng rest having a work engaging shoe which is movable into or out of engagement with the work, a movable splash guard mounted on said rest, means to move said shoe into or out of operative engagement with the work, and means operable in timed relation with the shoe movement to move said guard into or out of operative position so as to enable the operator to unload a work piece being ground after the grinding operation has been completed without the necessity of reaching over a high splash guard.

14. In a cylindrical grinding machine, a transversely movable rotatable grinding wheel, a ro-

tatable work support, a work steadyng rest having a work engaging shoe which is movable into and out of engagement with the work, a movable splash guard on the opposite side of the work support from the grinding wheel which is arranged to be moved into or out of operative position, means to move said shoe towards and from the work, and means operable in timed relation with said work shoe movement to move the guard into an operative position when the shoe is moved into engagement with the work.

15. In a cylindrical grinding machine, a rotatable grinding wheel, a rotatable work support, a work steadyng rest having a work engaging shoe which is movable into or out of engagement with the work, a movable splash guard which is arranged to be moved into or out of an operative position, means to move said shoe into or out of operative engagement with said work, yieldable means normally tending to hold said splash guard in an operative position, and means carried by said work shoe to move said guard to an inoperative position when the work shoe is moved away from the work.
